FEELER MECHANISM FOR LOOMS

Application filed May 14, 1929. Serial No. 362,917.

This invention relates to feeler mechanisms for looms, and is more particularly directed to feeler mechanisms of the "side slipping" type.

5 Feeler mechanisms of the side slipping type are now generally recognized as of two kinds, one in which the feeler is given its side slipping movement by means independent of the frontward pressure upon the feeler, and the other in which the feeler is given its side slipping movement by the frontward pressure of a surface within the shuttle on a detecting beat.

In feeler mechanisms of the second type, 15 the feeler is usually pivotally supported and subjected to the stress of a spring or other means tending to move the feeler laterally about its pivot into proper feeling position. Feeler mechanisms must be sensitive and responsive to the condition of the filling in the 20 shuttle, otherwise there is liable to be a change of filling at times when a sufficient working supply still remains in the shuttle, in which case there will result undesirable waste; or, 25 a change may not be called until the filling is completely exhausted, in which event an objectionable defect is liable to result in the cloth being woven. Either condition is objectionable and results from the fact that the 30 feeler itself is restrained from responding to the condition of the filling in the shuttle, and such restraint is generally exerted upon the feeler by a spring or similar device.

One of the objects of the present invention 35 is to provide a feeler mechanism of the side slipping type wherein the feeler is mounted for unrestrained pivotal movement and is moved to its proper feeling position about its pivotal mounting by means which acts upon 40 the feeler only as it approaches its rearward feeling position.

In accordance with the present invention, also, the means referred to is displaced by the feeler when the latter partakes of its side slipping movement when filling is substantially exhausted on a detecting beat.

The invention and novel features thereof will best be made clear from the following description and the accompanying drawings 50 of one good form thereof.

In the drawings:

Fig. 1 is a perspective view of a feeler mechanism containing the present invention and portions of the lay and shuttle with which the feeler cooperates;

Fig. 2 is a side elevation of the feeler mechanism;

Fig. 3 is a plan view showing the relation of parts when the feeler is moved frontwardly by a working supply of filling on detecting beat; and

Fig. 4 is a similar view showing the relation of parts when the feeler is displaced laterally by the frontward pressure of a surface within the shuttle when filling is substantially exhausted.

The feeler mechanism as shown is associated with filling replenishing mechanism, but since the details thereof form no part of the present invention and are now well understood in the art, the replenishing mechanism is not shown and described.

As usual in feeler mechanisms, the shipper stand is provided with a laterally extending support 1 having a slot 2 for a bracket 3 which may be adjustably secured in place by a suitable bolt 4.

Adjustably mounted upon the bracket 3 is the feeler stand 5 secured in the desired position by a bolt 6 which passes through a slot 7 formed in the feeler stand.

Mounted upon the feeler stand for movement towards and from the front of the loom is a slide which may be constituted, as shown, by an upper plate 8 and an under plate 9, the latter of which is mounted in a guideway 10 at one side of the feeler stand and held in sliding relation to the stand by an overlying clip 11 which is secured to the feeler stand by a screw 12. As shown, the slide may be formed of light sheet metal, if desired, and bent at its front portion to form the upper and lower plates 8 and 9 respectively.

The feeler stand 5 has an upwardly projecting flange 13 at its rear portion, and connected to the flange is a hook member 14 to which one end of a spring 15 is secured, the opposite end of the spring being connected to a lug 16 rising from the feeler slide, the effect being that the spring 15 normally tends

to move the slide into its rearward position.

The feeler 17 has an offset pivotal connection with the slide and, as shown, the feeler comprises a rearwardly extending arm 18 having filing engaging teeth 19 at its rear end and at its front end portion the feeler is provided with a laterally extending arm 20 which crosses to the opposite side of the feeler slide and is pivotally connected to the feeler slide at 21.

10 The laterally extending arm 17 is provided with a toe 22 at its free end and a stop 23 on the laterally extending arm 20 serves to limit the swinging movement of the feeler about its offset pivotal connection with the slide, as indicated in Fig. 4.

Associated with the feeler is a call plate 24 which is pivotally connected to the feeler stand at 25 and has an upstanding flange 26 which is in the path of the toe 22 of the feeler 20 as the feeler is moved rearwardly into feeling position, the result being that as the feeler is moved rearwardly under the impulse of the spring 15, the toe 22 of the feeler arm will engage the upstanding flange 26 of the call plate, as indicated by dotted lines, Fig. 3, and cause the feeler to be turned about its pivotal connection with the feeler slide 25 into proper feeling position.

30 The call plate 24 is extended frontwardly from its pivotal connection with the feeler stand at 25 and at its front portion has secured to it a transmitter 27, which, through a train of mechanism now well understood, 35 will initiate replenishment of filling when the feeler detects substantial exhaustion of filling in the shuttle on a detecting beat.

It may be desirable at times to provide the call plate with a light spring to normally maintain it in its normal position, as indicated in Fig. 3, and such spring may be coiled about the pivotal connection 25 of the call plate, as indicated at 28.

As indicated more clearly in Figs. 1 and 2, the call plate 24 is pivotally connected to the feeler stand at the under side thereof, in order that the call plate may have free swinging movement without interfering with other portions of the mechanism.

50 When a working supply of filling is present in the shuttle on a detecting beat, the toothed end portion 19 of the feeler will engage and sink into the filling, thereby normally preventing side slipping movement of the feeler, and as the lay moves frontwardly the slide 8 will be similarly moved. As the lay moves frontwardly, the pressure upon the end of the feeler becomes greater, and in case the feeler should side slip after it has been 55 moved frontwardly to a degree by the oncoming filling, it will be turned about its pivotal connection with the slide; but since the slide and feeler have both been moved frontwardly, the toe 22 of the feeler will not strike or 60 impinge upon the upstanding flange 26 of the 65

call plate, and filling replenishment will not be called. Should the filling be substantially exhausted on a detecting beat, however, the feeler will partake of its side slipping movement under the frontward pressure of the bobbin or filling carrier in the shuttle before it is moved frontwardly, with the result that the toe 22 connected by the lateral arm 20 with the feeler, will bear upon the upstanding flange 26 of the call plate and cause the latter to be turned about its pivotal support, as indicated in Fig. 2, whereupon filling replenishment will be initiated. 70 75

As hereinbefore stated, the feeler is mounted upon the feeler slide for unrestricted pivotal movement, so that upon backward movement of the lay after the feeler has been laterally displaced, the call plate will assume its normal position, as indicated in Fig. 3, and act upon the toe 22 of the feeler to return it to its proper feeling position. 80 85

The lay 29, only a portion of which is shown by Fig. 1, carries the usual shuttle box 30 for the reception of the shuttle 31 in which the filling carrier 32 is mounted, and the front wall 33 of the shuttle is provided with the usual feeler slot 34 as is also the front wall of the shuttle box, as usual, the parts being such that the feeler may enter the shuttle and feel for the filling on detecting beats. 95

What is claimed is:

1. In a feeler mechanism for looms, the combination of a feeler stand having a feeler carrying slide, a filling feeler having an offset pivotal connection with the slide and provided with a laterally extending toe, a call plate pivotally connected to the feeler stand and having a portion rearward of the feeler toe for engagement by the toe when the feeler is moved rearwardly to thereby swing the feeler into proper feeling position and to be moved rearwardly by the toe when the feeler side slips to effect movement of the call plate and a transmitter connected to the call plate to initiate filling replenishment. 100 105 110

2. In a feeler mechanism for looms, the combination of a feeler stand, a slide mounted on the feeler stand, a spring normally acting to move the slide rearwardly, a side slipping feeler having an offset pivotal connection with the slide and mounted for unrestrained pivotal movement relative to the slide, a toe extended laterally from the feeler, a call plate pivotally mounted on the feeler stand to swing in a horizontal plane and having an upstanding flange rearward of the feeler stand and feeler toe for engagement by the toe when the feeler is moved rearwardly to thereby swing the feeler into proper feeling position and to be moved rearwardly by the toe when the feeler side slips to cause the call plate to be swung in a horizontal plane, and a transmitter connected to the call plate for longitudinal movement thereby as it is

pivots moved to thereby initiate replenishment of filling.

3. In a feeler mechanism for looms, the combination of a feeler stand, a slide mounted on the feeler stand, a spring connected to the slide for moving it rearwardly, a feeler having a filling engaging portion and an arm extending laterally across the slide and having a toe, a pivot connecting the arm to the slide for unrestrained pivotal movement, a call plate pivotally connected to the under side of the feeler stand and having an upwardly projecting flange laterally at one side of its pivot rearward of the feeler toe for engagement by the toe to insure proper feeling position of the feeler as it moves rearwardly and effect turning movement of the call plate by rearward swinging movement of the toe when the feeler is displaced laterally on a detecting beat, and a transmitter movable longitudinally by the call plate when the latter is turned by the toe.

In testimony whereof, I have signed my name to this specification.

25 JESSE W. SIMPSON.
